(57) **CLAIM**

The ornamental design for a shoe, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a front left perspective view of a shoe showing my new design;

FIG. 2 is a front right perspective view thereof;

FIG. 3 is a top front perspective view thereof;

FIG. 4 is a top elevational view thereof;
FIG. 5 is an enlarged view thereof taken from line 5-5 shown in FIG. 1; and,

FIG. 6 is a left-side elevational view thereof.

The evenly dashed broken lines depict portions of the shoe that form no part of the claimed design. The dash-dot-dash broken lines adjacent to claimed surfaces illustrate the claim boundary and form no part of the claimed design. The peripheral dash-dot-dash broken lines in FIGS. 1 and 5 illustrate the cut line of the enlarged view and form no part of the claimed design. The speckles depict claimed surface indicia and not surface shading.
